UNITED STATES PATENT OFFICE.

ARTHUR W. WALKER, OF MALDEN, MASSACHUSETTS.

COOKING-STOVE.

1,163,719.

Specification of Letters Patent. Patented Dec. 14, 1915.

Application filed September 19, 1914. Serial No. 862,528.

To all whom it may concern:

Be it known that I, ARTHUR W. WALKER, a citizen of the United States, residing at Malden, in the county of Middlesex and 5 State of Massachusetts, have invented new and useful Improvements in Cooking-Stoves, of which the following is a specification.

This invention relates to improvements in 10 cooking stoves.

More particularly it relates to an improved means for controlling the flow of air, and of the products of combustion, for controlling the generation and distribution of 15 heat so that all the various dampers or valves are automatically associated in correct positions according to the effect desired. An indicator or master handle is provided; and the user of the stove moves this to either 20 of three positions in one of which the valves, through their connections, are all set in proper position for kindling, in another for checking, and in another for baking.

In Letters Patent No. 605,303, granted to 25 me on June 7, 1898, is shown a cooking stove in which two openings to the smoke pipe are provided in combination with a single damper which may substantially cover either one or both of the openings, thus providing, 30 so far as the entrance to the smoke pipe is concerned, for a proper setting of the dampers by the control of a single knob. Such a damper fails to cover a complete cooking stove because as such stoves have heretofore 35 been constructed no means has been provided which automatically insures correct setting of the damper which admits air to the under side of the grate, commonly called the "draft."

40 It is an object of the present invention to provide such a combination, with the result of materially simplifying the management of the cooking stove.

Where there are three possible settings 45 for the two passages into the smoke pipe, and two possible settings for the "draft" controlling the flow of air for combustion, a person using the stove may easily fail to get the precise combination of settings that 50 is proper; and it is a fact that ranges often fail to give good or satisfactory service for this very reason.

It is the aim of the present invention to 55 avoid the possibility of this by providing a control for the air entering to the grate in combination with the control which di-

rects the products of combustion around the oven, or short circuits them direct to the chimney flue, and that which controls the chimney flue itself.

In the invention hereinafter disclosed, I have arranged a door or valve and its connections so as to control the admission of air for combustion in harmony with the dampers controlling the flow of the gaseous 60 products of combustion, so as to effect a full and complete regulation of the direction and quantity of gases flowing within the stove in a manner never before attempted so far as I am aware.

It is also an object of the invention to provide for a separate opening of the air draft, apart from the combination, whenever that may be desired without interfering with the setting of the other parts of the 70 combined arrangement.

It is the intent of the patent to cover by the appended claims whatever features of 75 patentable novelty exist in the invention disclosed.

In the accompanying drawings which 80 illustrate an embodiment of the invention and modifications thereof, Figure 1 is a rear elevation of a cooking stove embodying the invention; Fig. 2 is a side elevation of the 85 same; Fig. 3 is a perspective of a modification; and Fig. 4 is a rear elevation of another modification.

Referring to the drawings, 10 indicates the body of the cooking range, 11 its top, 90 12 its grate, and 13 the beginning of its smoke pipe or flue. In the form here illustrated there are two openings marked respectively 14 and 15 through either of which the gaseous products of combustion 95 may go from the stove to the smoke pipe; and there is an opening 16 through which air may reach the under side of the grate 12 for combustion. A damper, consisting of a plate or door, 17, closes the latter opening; and a damper, consisting of a sliding 100 plate, 18, is so arranged that it may close either or both of the openings 14 and 15. The invention provides means for connecting these various dampers. The dampers 105 controlling the openings 14 and 15 may preferably be arranged as shown in my said Letters Patent; and one embodiment of this is illustrated in Fig. 1 of the drawings where the plate 18 is connected by a rod 19 110 to a stem and knob 20 which may be moved through a slot 21 to either of three positions,

A, B and C. As illustrated, a setting in position A corresponds to the arrangement of the smoke pipe inlet suitable for kindling the fire, the hole 14 being open to admit gases directly from the grate to the chimney pipe 13. A setting in position B is suitable for checking the fire, both of the inlets 14 and 15 being substantially closed, so that the gases of combustion can pass away from the grate into the smoke pipe through either of the openings 14 and 15, only at a minimum rate. The position C corresponds to the arrangement of the damper plate 18 for baking, closing the direct opening 14 and leaving the hole 15 open, it being understood that the range has the usual interior partitions and passages such that when the opening 14 is closed the products of combustion have to pass around the over 13' before they can reach the opening 15 to get into the smoke pipe. The "draft" door 17 for controlling the flow of air to the under side of the grate has ordinarily a simple movement in one direction to admit and in the opposite direction to shut off the air. The movement of the damper plate 18 from position A through position B to position C is continuous in direction; yet at one of these positions, A, the "draft" 17 ought to be opened, in the next, B, it ought to be closed, and in the next, C, it ought to be open, in order to get the most efficient as well as the most effective operation of the range. The invention provides mechanism by which this may be accomplished consisting, in the preferred form, in the provision of a pivotal mounting for the draft door 17, with a lug 29 in position to be engaged by a rocker arm 22 and pushed thereby in the direction to open the door 17, leaving that door free to be moved still farther in the same direction. A catch, which may preferably be a gravity latch, 23, is provided to hold the door 17 when wider open. The rocker arm 22, pivoted at 24, is operated by a connecting rod 25 which is pivoted thereto at 26 and is at its other end attached pivotally to the stem and handle 20. This pivot 26 between the connecting rod 25 and the rocker arm 22 is at the opposite end of the latter from where it engages the lug 29; and in the form of the invention illustrated is directly under the position B of the handle 20. As the movement of the upper end of this connecting rod 25 is rectilinear, going equal distances to the left and to the right of the position which it occupies when the connecting rod stands vertical, and as the rod 25 is inextensible, and as the parts are constructed so that the pivot 26 is slightly below the level of the pivot 24 of the rocker arm, when the connecting rod 25 is vertical, it follows that this pivot 26 is raised somewhat when the upper end of the con-

necting rod 25 is moved rectilinearly to the left or to the right, because the lower end of this arm can move only through the vertical arc in which the pivot 26 swings around the center 24. As a result, a movement of the handle 20, either to position A or to position C, raises the pivot 26 and depresses the end of the rocker arm 22 which is in engagement with the lug 29, and so opens the "draft" 17. The movement of the handle 20 to the position B from either of the positions A or C closes the door 17, or at least permits it to be closed. Accordingly, when the handle 20 is in position A, which is the position for kindling, the "draft" 17 is necessarily open, and the hole 14 leading directly from the fire to the beginning of the smoke pipe 13 is also necessarily open. When the handle is in position B both of these are closed, so far as the automatic action of the apparatus is concerned. When the handle is in position C, which position it should occupy when it is desired to heat the oven, the door 17 is necessarily open, thereby correcting the error into which some persons fall, of condemning a range because it does not bake satisfactorily whenever the passage 15 is open which leads around the oven, while keeping the "draft" 17 closed. By reason of the fact that the lug 29 swings away from the rocker arm 22, it is possible for the user to open the door 17 wide, by hand, to get access to the grate for poking out ashes or for any other purpose.

A modified form of the invention is illustrated in Fig. 3 in which the door 17' corresponds to the door 17 of Fig. 1, and the rocker arm is omitted, one end of the connecting rod 25' being pivoted to the handle 20 as before, while the other end is attached loosely to the door 17' in such a way that can not follow the movement of the handle 20 to the right or left. That end of the rod must therefore rise; and the door is hinged so that it will be opened when the lower end of the rod 25' is thus raised.

Another modification of the invention is illustrated in Fig. 4 where the plate 17" corresponds to the door 17 and is arranged 115 to slide horizontally, covering either one or both of two draft openings 17''' which lead to the under side of the grate. The slide is operated by a lever 25" pivoted at 27, with a pin-and-slot connection. When the handle 120 20 is in its medial or checking position B the sliding plate 17" is in its medial position closing both of the draft openings 17''' but when the handle 20 is moved toward either of its side positions A or C the co-incident 125 movement of the sliding plate 17" moved in the opposite direction opens one of the openings to the grate, for the admission of air for combustion.

While the invention has been shown as it 130

may be applied to a range in which the passages for baking and kindling are controlled by a combination damper, the principles of the invention can also be applied 5 to cases where these passages are controlled by separate dampers, and various other modifications may be made from the precise structure illustrated, without departing from the scope of the patent as defined in the appended claims.

In reading the claims it will be understood that closure of the dampers into the smoke pipe for the checking position is only approximate, it being necessary that there 15 be always a little space allowed for escape of gases, according to customary practice. The intake damper is preferably so arranged that it tends automatically to be closed by gravity. When it is so closed all of the 20 dampers are held in position by gravity; but there should be sufficient friction of the parts so that when it is open its weight will not move them out of the position to which they have been adjusted. The handle can 25 then be left in various intermediate positions, with effects varying according to its distance from the extreme positions illustrated.

In the particular stove illustrated in the 30 drawings there is an appreciable space between the openings 14 and 15, which may happen in some designs of stoves, and which is advantageous for some purposes, but it will be understood that the space between 35 these two openings may be much less than that portrayed, producing incidental changes either in the size of the openings or in the travel of the handle 20.

I claim as my invention:

40 1. In a cooking stove having a grate with openings for intake of air and discharge of gases to a smoke pipe, the combination of dampers controlling the said openings, and connections between the dampers, and 45 a master member joined to said connections having a handle adapted to slide horizontally along the top of the stove and another part adapted to move vertically when the handle moves horizontally, movement of 50 which master member effects predeterminate movement of said dampers simultaneously.

2. The combination, in a stove having a grate, a direct passage therefrom to the smoke pipe, an oven, and an alternative pas-

sage to the smoke pipe going around the 55 oven, of dampers for the said passages and the intake of air to the grate, and operating connections associating a closed position of the intake damper with approximate closure of the smoke pipe and associating an open 60 position of the intake with an opening of either passage to the smoke pipe.

3. The combination, in a stove having a grate and discharge passage to a smoke pipe, of dampers controlling the admission 65 of air to the grate and the escape of gases to the smoke pipe, and connections between them including an operating handle movable progressively through three locations, movement of which handle effects predeterminate movements of both dampers simultaneously through three corresponding 70 settings during which respectively the intake damper is open, is closed, and then is open again, the intake damper being movable to wide open position independently of said connections.

4. The combination, in a stove having a grate and a direct and an indirect passage therefrom to the smoke pipe, of dampers 80 controlling the said passages and the intake of air to the grate, a handle controlling them all, movable between three positions, the medial position corresponding to a closed position of all of said dampers. 85

5. The combination, in a stove having a grate and a direct and an indirect passage therefrom to the smoke pipe, of dampers controlling the said passages and the intake of air to the grate; a handle for controlling 90 them all, movable between three positions, the medial position corresponding to a closed position of all of said dampers; and connections, including a horizontally moving part for the smoke pipe passages and a 95 rod depending loosely therefrom for the air intake, said rod being vertical when the handle is in medial position, and inclined when it is out of medial position, whereby the lower end of said rod is raised and lowered by said horizontal movement from and toward said medial position. 100

Signed by me at Boston, Mass., this 12th day of September, 1914.

ARTHUR W. WALKER.
